J. SARDO,
LIFTING JACK.
APPLICATION FILED JUNE 18, 1918.

Patented Oct. 1, 1918.

UNITED STATES PATENT OFFICE

JACOB SARDO, OF JOHNSTOWN, PENNSYLVANIA.

LIFTING-JACK.

1,280,309.

Specification of Letters Patent. Patented Oct. 1, 1913.

Application filed June 18, 1913. Serial No. 240,619.

To all whom it may concern:

Be it known that I, JACOB SARDO, a citizen of the United States, residing at Johnstown, in the county of Cambria and State of Pennsylvania, have invented certain new and useful Improvements in Lifting-Jacks, of which the following is a specification.

My invention relates to lifting jacks, and is specially designed for use on railroads. 10 It is used to lift cars, engines, and obstructions on the tracks, and is very useful in repair work.

The object is to provide a device of this character which will be simple in construction, and yet strong and durable, and capable of resisting hard usage.

Another object is to provide a jack with which one person may lift a very heavy load, though adapted to be operated by two persons, and having a wide range of lifting movement.

A further object is to provide a jack of this character which can be conveniently handled and moved along on the railroad track, as the needs of the service may require, without having to be bodily lifted and carried from place to place.

Still another object is to provide means for shifting the jack at its bottom while it is supporting a load, when it is found desirable to do so.

Other minor objects will appear in the subjoined description.

The invention consists in certain novel features of construction and arrangement of parts, as will be hereinafter described and claimed, reference being had to the accompanying drawings, in which:—

Figure 1 is a side elevation of the device. 40 Fig. 2 is an elevation of the rear side thereof. Fig. 3 is a perspective view. Fig. 4 shows an extension section of the lifting rack. Fig. 5 is a sectional view taken on the line 5—5 of Fig. 2, looking in the direction of the arrow, to show the arrangement for operating the lifting rack, the parts of the device below said arrangement being omitted for clearness; and, Fig. 6 shows a sectional view taken on the line 6—6 of Fig. 2, looking in the direction of the arrow.

My device may be made of any suitable material, but I usually employ steel in its construction.

Referring further to the drawings, the 55 numeral 1 indicates the frame of the jack

which may be formed of a single piece of metal bent into the form of a box as shown, or it may be formed of a number of pieces united together by screws or in any other preferred manner. In one of its narrower sides the frame is provided with a longitudinal opening or slot 2 extending the entire length thereof, and in this slot the lifting rack 3 moves up and down. The frame has a lid 4 suitably secured thereto and provided with an opening 5 through which the lifting rack passes, as shown in Fig. 3. The frame 1 is provided in its upper portion with parallel shafts 6 and 7 journaled in the sides of the frame, and on these two shafts are carried intermeshing gear wheels 8 and 9 respectively, with the wheel 8 also intermeshing with the lifting rack 3. Ratchet wheels 10 and 11 are mounted on the shaft 7 outside the box or frame 1, and the shaft has a crank 12 adjacent the ratchet wheel 10, which is provided with a co-operating pawl 13.

When the load to be lifted is too heavy to be lifted in the ordinary way with the crank 12, I employ an auxiliary lifting arrangement consisting of the lever 14 used in connection with the ratchet wheel 11. This lever works on a pivot 15 and is provided with a slot 16 so that it can be moved back and forth to conveniently engage the successive teeth of the ratchet wheel 11 to rotate the same by a downward movement of the outer end of the lever.

The rack 3 is provided with a head 17 of any usual or preferred form, and with a plurality of claws 18 located at different heights from the ground to adapt the device to engage loads at different points of elevation. These claws project outwardly from the slot 2, and are provided with guide blocks 19 rigidly secured thereto, which co-operate with the shoulders 20 on the rack at the inner side of said slot, as more clearly illustrated in Fig. 5.

Any other ordinary arrangement of lifting rack and guiding means therefor may be employed equally well with my construction.

In order that the rack may have great range of longitudinal movement to adapt the jack to exceptional cases where an unusually high lift is to be made, I form the rack in two sections, the lower section 3^a being illustrated in Fig. 4. The lower end of the upper section 3 is provided with a bore 21, and the upper end of the lower section 3^a is provided

with a pin 22 which takes into said bore when it is desired to use the lower section 3^a of the rack.

Special attention is now called to an important feature of my invention employed for moving it along the railroad track, and also for shifting the lower end of the jack while it is supporting a load. The frame 1 is provided near its lower end with a shaft 23 parallel with the shafts 6 and 7. This shaft 23 is journaled in opposite sides of the frame, and has three wheels rigidly secured to it, namely, a flanged wheel 24 approximately at its center, and two smaller wheels 25 on its outer ends which ends project sufficiently beyond the sides of the box or frame to receive these smaller wheels. These wheels 25 are provided with a plurality of openings 26. Figs. 2 and 6 of the drawings very clearly illustrate the arrangement just described. At a suitable distance above the wheels 25, the handles 27 are pivotally mounted on the sides of the frame, and are adapted to drop down into parallelism with the frame when not in use. When it is desired to use the handles to move the jack, they are swung up into a horizontal position as indicated in dotted lines in Fig. 2, in which position the corners 28 at the upper end of the handles come into abutting engagement with the handle mountings 29, to hold the handles against further upward movement.

The wheel 24 projects somewhat below the lower end of the frame 1, and is designed to run along one of the rails of the railroad track when desired in moving the device.

Sometimes in lifting one end of a burden while the other end remains on the ground or at least in a stationary position, the lifted end of the load travels in the arc of a circle and moves to some extent horizontally away from the base of the jack which remains stationary on its support. The result of this is that in making very high lifts, or lifts in which the lifted end of the burden is only a comparatively short distance from the stationary end thereof, it sometimes becomes very desirable to move the lower end of the jack a little nearer to the burden, to follow up the load, so to speak. This will at times be specially true when the load is to be lifted so high that the lower section 3^a of the lifting rack is employed. Moreover, the heavier the load supported by the jack the greater will be the importance at times of being able to move the base of the jack toward the load as just described. Whenever it thus becomes necessary to move the base of the jack forward on the railroad track toward the load being lifted, the outer end 14^a of the lever 14, or any other suitable tool, is inserted in one of the openings 26 of the wheels 25 and the lever is then moved forwardly to impart forward rotation to the

flanged wheel 24, which will move the base of the jack toward the work. A rearward movement of the lever would, of course, move the base of the jack from the work, if that were ever desired.

The shaft 23 is journaled a suitable distance above the lower end of the jack to prevent the wheels 25, which are of less diameter than the wheel 24, from projecting beyond the bottom of the jack, where they would be unduly exposed.

The jack is provided on its bottom with removable brads 30 which may be used under circumstances where there would be danger of the bottom of the jack slipping under its load, as for instance when the jack stands on icy ground.

Special attention is now directed to applicant's unique arrangement of parts which enables one man to simultaneously operate both the crank 12 and the lever 14. With the arrangement of the parts as shown, the operator ordinarily stands behind the jack facing his work and turns the crank forwardly with his right hand. This brings his left hand next to the lever 14 so that he can most conveniently operate the lever with his left hand while operating the crank with his right hand. Moreover, in very heavy work, when the operator is giving a very strong upward pull on the crank 12 with his right hand, he can place his left hand on the lever 14 and bear down thereupon, thereby utilizing the lever 14 to gain a stronger purchase in lifting the crank 12.

The principle just referred to applies so fully that if the operator places his right hand on the crank 12, when in its downward position, and his left hand on the lever 14, and then moves his hands farther apart by drawing up his right hand—holding the crank—toward him, and moving his left hand outwardly from him—pushing the lever downwardly—the device will be operated in a powerful manner. In this case, the crank forms a purchase for operating the lever and the lever forms a purchase for operating the crank, and the power applied in the operation is only limited by the power of the operator to spread his arms apart, toggle fashion, drawing one toward him and pushing the other from him. In fact, the operator virtually makes of himself for the time being, a toggle for simultaneously operating the crank and lever. In this way a skilful person is able to exert tremendous power; and hence it will be seen that this special arrangement will permit one person to lift a prodigious load when he has to work alone, and will thus enable one man working by himself to do heavy work that would ordinarily require two or three men.

Having thus described the principles of my invention, and shown one method of

practically embodying the same, I yet do not wish to be limited to the exact showing made, but desire protection on all that comes clearly within the spirit and scope of my invention.

What I claim as new and desire to protect by Letters Patent is:—

A device of the character described, comprising a frame provided with means for elevating a load, said means being adapted to engage the load at the front side of the jack, and including a crank at one side of the

jack adapted to be rotated forwardly from the rear side of the frame by one hand of the operator, and a lever extending rearwardly from the opposite side of the frame adjacent to the other hand of the operator when standing at the rear side of the jack facing the load; whereby to permit the operator to simultaneously work both the crank and the lever while facing the work.

In testimony whereof I affix my signature.

JACOB SARDO.
